(57) **CLAIM**

We claim the ornamental design for a depth gauge, as shown and described.

DESCRIPTION

FIG. 1: Is a perspective view of the depth gauge showing the new, original and ornamental design;
FIG. 2: is a front view thereof;
FIG. 3: is a first side view thereof;
FIG. 4: is a back view thereof;
FIG. 5: is a second side view thereof;
FIG. 6: is a top view thereof; and,
FIG. 7: is a bottom view thereof.
